(57) **ABSTRACT**

A perforated plate for a gas turbine combustor according to at least one embodiment is a perforated plate provided between a combustor basket and a combustor casing of the gas turbine combustor and fixed to an outer peripheral portion of the combustor basket. In a hole arrangement area with a plurality of through holes of the perforated plate, a region close to the combustor basket has a larger average value of a ligament ratio than a region close to the combustor casing, where the ligament ratio is obtained by dividing a distance between outer peripheral edges of two adjacent holes of the plurality of through holes by a distance between centers of the two holes.

**PERFORATED PLATE FOR GAS TURBINE
COMBUSTOR, GAS TURBINE COMBUSTOR,
AND GAS TURBINE**

TECHNICAL FIELD

The present disclosure relates to a perforated plate for a gas turbine combustor, a gas turbine combustor, and a gas turbine.

The present application claims priority based on Japanese Patent Application No. 2020-149132 filed on Sep. 4, 2020, the entire content of which is incorporated herein by reference.

BACKGROUND ART

In a gas turbine combustor, a flow conditioning plate (perforated metal) is often placed between a combustor basket and a combustor casing of the gas turbine combustor to suppress unbalanced air flow in the gas turbine combustor (see Patent Document 1, for example).

CITATION LIST

Patent Literature

Patent Document 1: JP2017-9262A

SUMMARY

Problems to be Solved

For example, when the flow conditioning plate is welded and fixed to the combustor basket of the gas turbine combustor, the flow conditioning plate oscillates due to combustion oscillation during operation, and a large stress acts on the fixed portion of the flow conditioning plate on the combustor basket side. This may cause deformation of the flow conditioning plate or damage such that holes of the flow conditioning plate are connected to each other.

In view of the above, an object of at least one embodiment of the present disclosure is to suppress deformation or damage of a flow conditioning plate provided between a combustor basket and a combustor casing of a gas turbine combustor.

Solution to the Problems

(1) A perforated plate for a gas turbine combustor according to at least one embodiment of the present disclosure is a perforated plate provided between a combustor basket and a combustor casing of the gas turbine combustor and fixed to an outer peripheral portion of the combustor basket. In a hole arrangement area with a plurality of through holes of the perforated plate, a region close to the combustor basket has a larger average value of a ligament ratio than a region close to the combustor casing, where the ligament ratio is obtained by dividing a distance between outer peripheral edges of two adjacent holes of the plurality of through holes by a distance between centers of the two holes.

(2) A gas turbine combustor according to at least one embodiment of the present disclosure is provided with the perforated plate having the above configuration (1).

(3) A gas turbine according to at least one embodiment of the present disclosure is provided with the gas turbine combustor having the above configuration (2).

Advantageous Effects

According to at least one embodiment of the present disclosure, it is possible to suppress deformation or damage of a flow conditioning plate provided between a combustor basket and a combustor casing of a gas turbine combustor.

BRIEF DESCRIPTION OF DRAWINGS

FIG. 1 is a schematic configuration diagram of a gas turbine according to some embodiments.

FIG. 2 is a cross-sectional view of a combustor according to some embodiments.

FIG. 3 is a cross-sectional view of a main portion of a combustor according to some embodiments.

FIG. 4 is a perspective view of a combustor basket and a flow conditioning plate according to some embodiments, viewed from the downstream side of an air passage.

FIG. 5 is a cross-sectional view of the combustor basket and the flow conditioning plate according to some embodiments, taken along line A-A in FIG. 3.

FIG. 6 is a diagram for describing holes of the flow conditioning plate according to some embodiments.

FIG. 7A is an example of a graph showing a radial distribution of ligament ratio.

FIG. 7B is an example of a graph showing a radial distribution of increase rate of ligament ratio.

FIG. 8A is an example of a graph showing a radial distribution of ligament ratio.

FIG. 8B is an example of a graph showing a radial distribution of increase rate of ligament ratio.

FIG. 9A is an example of a graph showing a radial distribution of ligament ratio.

FIG. 9B is an example of a graph showing a radial distribution of increase rate of ligament ratio.

FIG. 10A is an example of a graph showing a radial distribution of ligament ratio.

FIG. 10B is an example of a graph showing a radial distribution of increase rate of ligament ratio.

FIG. 11 is a diagram showing an example of another embodiment of the size of holes.

FIG. 12 is a diagram showing an example of another embodiment of the size of holes.

FIG. 13 is a diagram showing an example of another embodiment of the size of holes.

DETAILED DESCRIPTION

Embodiments of the present disclosure will be described below with reference to the accompanying drawings. It is intended, however, that unless particularly identified, dimensions, materials, shapes, relative positions, and the like of components described in the embodiments shall be interpreted as illustrative only and not intended to limit the scope of the present disclosure.

For instance, an expression of relative or absolute arrangement such as "in a direction", "along a direction", "parallel", "orthogonal", "centered", "concentric" and "coaxial" shall not be construed as indicating only the arrangement in a strict literal sense, but also includes a state where the arrangement is relatively displaced by a tolerance, or by an angle or a distance whereby it is possible to achieve the same function.

For instance, an expression of an equal state such as "same" "equal" and "uniform" shall not be construed as indicating only the state in which the feature is strictly equal, but also includes a state in which there is a tolerance or a difference that can still achieve the same function.

Further, for instance, an expression of a shape such as a rectangular shape or a cylindrical shape shall not be construed as only the geometrically strict shape, but also includes a shape with unevenness or chamfered corners within the range in which the same effect can be achieved.

On the other hand, an expression such as "comprise", "include", "have", "contain" and "constitute" are not intended to be exclusive of other components.

(Gas Turbine 1)

FIG. 1 is a schematic configuration diagram of a gas turbine according to some embodiments.

With reference to FIG. 1, a gas turbine, which is an example of application of a gas turbine combustor and a perforated plate of the gas turbine combustor according to some embodiments, will be described.

As shown in FIG. 1, a gas turbine 1 according to some embodiments includes a compressor 2 for producing compressed air that serves as an oxidant, a gas turbine combustor 4 for producing combustion gas using the compressed air and fuel, and a turbine 6 configured to be driven by the combustion gas to rotate. In the case of the gas turbine 1 for power generation, a generator (not shown) is connected to the turbine 6, so that rotational energy of the turbine 6 generates electric power. In the following description, the gas turbine combustor 4 is also simply referred to as the combustor 4.

A specific configuration example of each component of the gas turbine 1 according to some embodiments will be described.

The compressor 2 according to some embodiments includes a compressor casing 10, an air inlet 12 disposed on the inlet side of the compressor casing 10 for sucking in air, a rotor 8 disposed so as to pass through both the compressor casing 10 and a turbine casing 22, which will be described later, and a variety of blades disposed in the compressor casing 10. The variety of blades includes an inlet guide vane 14 disposed adjacent to the air inlet 12, a plurality of stator vanes 16 fixed to the compressor casing 10, and a plurality of rotor blades 18 implanted on the rotor 8 so as to be arranged alternately with the stator vanes 16. The compressor 2 may include other components, such as an extraction chamber (not shown). In the compressor 2, the air sucked in from the air inlet 12 flows through the plurality of stator vanes 16 and the plurality of rotor blades 18 to be compressed into compressed air having a high temperature and a high pressure. The compressed air having a high temperature and a high pressure is sent to the combustor 4 of a latter stage from the compressor 2.

The combustor 4 according to some embodiments is disposed in a casing 20. As shown in FIG. 1, a plurality of combustors 4 may be arranged annularly around the rotor 8 inside the casing 20. The combustor 4 is supplied with fuel and the compressed air produced by the compressor 2, and combusts the fuel to produce combustion gas that serves as a working fluid of the turbine 6. The combustion gas is sent to the turbine 6 of a latter stage from the combustor 4. The configuration example of the combustor 4 according to some embodiments will be described later in detail.

The turbine 6 according to some embodiments includes a turbine casing 22 and a variety of blades disposed in the turbine casing 22. The variety of blades includes a plurality of stator vanes 24 fixed to the turbine casing 22 and a

plurality of rotor blades 26 implanted on the rotor 8 so as to be arranged alternately with the stator vanes 24. The turbine 6 may include other components, such as an outlet guide vane. In the turbine 6, the rotor 8 is driven to rotate as the combustion gas passes through the plurality of stator vanes 24 and the plurality of rotor blades 26. In this way, the generator connected to the rotor 8 is driven.

An exhaust chamber 30 is connected to the downstream side of the turbine casing 22 via an exhaust casing 28. The combustion gas having driven the turbine 6 is discharged outside through the exhaust casing 28 and the exhaust chamber 30.

(Combustor 4)

FIG. 2 is a cross-sectional view of a combustor according to some embodiments. FIG. 3 is a cross-sectional view of a main portion of a combustor according to some embodiments.

With reference to FIGS. 2 and 3, a specific configuration of the combustor 4 according to some embodiments will be described.

As shown in FIGS. 2 and 3, multiple combustors 4 according to some embodiments are arranged annularly around the rotor 8 (see FIG. 1). Each combustor 4 includes a combustion liner 46 disposed in a combustor casing space 40 defined by the casing 20, and a pilot combustion burner 50 and a plurality of premixed combustion burners (main combustion burners) 60 arranged inside the combustion liner 46. The combustor 4 further includes a combustor casing 45 disposed around the outer periphery of a combustor basket 47 of the combustion liner 46 inside the casing 20. An air passage 43 through which the compressed air flows is formed between the outer periphery of the combustor basket 47 and the inner periphery of the combustor casing 45.

The combustor 4 may include other components, such as a bypass line (not shown) allowing the combustion gas to bypass.

In the combustor 4 according to some embodiments, a flow conditioning plate 100 is disposed in the air passage 43. The flow conditioning plate 100 is a perforated plate provided between the combustor basket 47 and the combustor casing 45 and fixed to an outer peripheral portion of the combustor basket 47. The flow conditioning plate 100 has a plurality of through holes (holes 110). The flow conditioning plate 100 according to some embodiments will be described later in detail.

For example, the combustion liner 46 includes a combustor basket 47 disposed around the pilot combustion burner 50 and the plurality of premixed combustion burners 60, and a transition piece 48 connected to a tip portion of the combustor basket 47.

The pilot combustion burner 50 is disposed along the central axis of the combustion liner 46. The premixed combustion burners 60 are arranged at a distance from one another so as to surround the pilot combustion burner 50.

The pilot combustion burner 50 has a pilot nozzle (nozzle) 54 connected to a fuel port 52, a pilot cone 56 disposed so as to surround the pilot nozzle 54, and a swirler 58 disposed on the outer periphery of the pilot nozzle 54.

Each premixed combustion burner 60 has a main nozzle (nozzle) 64 connected to a fuel port 62, a burner cylinder 66 disposed so as to surround the nozzle 64, an extension tube 65 connecting the burner cylinder 66 and the combustion liner 46 (for example, combustor basket 47), and a swirler 70 disposed on the outer periphery of the nozzle 64.

In the combustor 4 having the above configuration, the compressed air having a high temperature and a high pressure generated by the compressor 2 is supplied into the

combustor casing space 40 through a casing inlet 42, and then is introduced from the combustor casing space 40 to the burner cylinder 66 through the air passage 43. The compressed air flowing through the air passage 43 is conditioned by passing through the plurality of holes 110 formed in the flow conditioning plate 100. Then, the compressed air and the fuel supplied from the fuel port 62 are premixed in the burner cylinder 66. At this time, the premixed air is mainly formed into a swirl flow by the swirler 70, and flows into the combustion liner 46. Further, the compressed air and the fuel injected from the pilot combustion burner 50 via the fuel port 52 are mixed in the combustion liner 46 and ignited by a pilot light (not shown) to be combusted, whereby the combustion gas is produced. At this time, a part of the combustion gas diffuses to the surroundings with flames, which ignite the premixed air flowing into the combustion liner 46 from each premixed combustion burner 60 to cause combustion. That is, the pilot flames produced by the pilot fuel injected from the pilot combustion burner 50 hold flames for stable combustion of the premixed air (premixed fuel) from the premixed combustion burners 60.

(Flow Conditioning Plate (Perforated Plate) 100)

FIG. 4 is a perspective view of a combustor basket and a flow conditioning plate according to some embodiments, viewed from the downstream side of the air passage. In FIG. 4, holes 110, which will be described later, are not depicted.

FIG. 5 is a cross-sectional view of the combustor basket and the flow conditioning plate according to some embodiments, taken along line A-A in FIG. 3.

FIG. 6 is a diagram for describing holes of the flow conditioning plate according to some embodiments.

In the following description, the radial direction with respect to the central axis AX of the combustor basket 47 is referred to as the radial direction of the combustor 4 or simply the radial direction. Further, in the following description, the circumferential direction with respect to the central axis AX of the combustor basket 47 is referred to as the circumferential direction of the combustor 4 or simply the circumferential direction.

The flow conditioning plate 100 according to some embodiments is a perforated plate provided at an inlet portion of the air passage 43 and having a large number of holes 110 for connecting the upstream and downstream sides of the air passage 43. The flow conditioning plate 100 according to some embodiments is a ring-shaped plate member and is configured to surround the combustor basket 47. The flow conditioning plate 100 according to some embodiments is provided with ribs 161 at equal intervals in the circumferential direction for fixing the flow conditioning plate 100 at the downstream side of the flow conditioning plate 100 in the air passage 43. The ribs 161 are radially arranged in the radial direction so that both ends are in contact with the combustor basket 47 and a ring member 163 disposed to face the inner peripheral surface of the combustor casing 45. In the following description, the flow conditioning plate 100 is also referred to as a perforated plate 100.

The perforated plate 100 according to some embodiments is joined to an outer peripheral portion of the combustor basket 47 by welding. That is, a radially inner end portion 101 of the perforated plate 100 according to some embodiments is joined to an outer peripheral surface 47b of the combustor basket 47 by welding.

In the combustor 4 according to some embodiments, a radially inner end portion 161a of the rib 161 is joined to the outer peripheral surface 47b of the combustor basket 47 by fillet welding.

In the combustor 4 according to some embodiments, a radially outer end portion 161b of the rib 161 is joined to an inner peripheral surface 163a of the ring member 163 by fillet welding.

5 The perforated plate 100 according to some embodiments is joined by welding to the rib 161 and the ring member 163 at a fillet weld portion 165 between the end portion 161b of the rib 161 and the inner peripheral surface 163a of the ring member 163 in the vicinity of a radially outer end portion 103 on a surface 100d of the perforated plate 100 facing downstream in the air passage 43.

When the perforated plate 100 is fixed to the outer peripheral portion of the combustor basket 47 as in some embodiments, the combustion oscillation during operation of the gas turbine 1 causes a region of the perforated plate 100 close to the combustor casing 45 to oscillate against the fixed portion of the perforated plate 100 close to the combustor basket 47. Accordingly, the stress acting on the perforated plate 100 due to the oscillation increases from the 15 radially outer side to the radially inner side. Therefore, when such oscillation of the perforated plate 100 occurs, the stress acting on the fixed portion of the perforated plate 100 adjacent to the combustor basket 47 increases, which may cause deformation of the perforated plate 100 or damage 20 such that the holes 110 of the perforated plate 100 are connected to each other.

25 In order to reduce the stress, it is conceivable to reduce the aperture ratio of the holes 110 (the area of holes 110 per unit area) in the perforated plate 100 and increase the area of the 30 region without holes 110. However, generally, it is desirable to increase the aperture ratio of the flow conditioning plate from the viewpoint of ensuring the flow rate of air passing through the plurality of holes.

35 Therefore, in some embodiments, the above-described problem is solved by configuring the perforated plate 100 as follows. Specifically, in some embodiments, in a hole arrangement area 105 with a plurality of through holes (holes 110), a region close to the combustor basket 47 (inner region 108a) has a larger average value of a ligament ratio 40 (P2/P1) than a region close to the combustor casing 45 (outer region 108b), where the ligament ratio is obtained by dividing a distance P2 between outer peripheral edges 109 of two adjacent holes 110 of the plurality of through holes (holes 110) by a distance P1 between the centers of the two 45 holes 110. That is, in some embodiments, the perforated plate 100 is configured such that, in the hole arrangement area 105 with a plurality of through holes (holes 110), a region close to the combustor basket 47 (inner region 108a) has a larger average value of the ligament ratio (P2/P1) than 50 a region close to the combustor casing 45 (outer region 108b).

55 This configuration will now be described.

In the perforated plate 100 according to some embodiments, as described above, the ribs 161 are radially arranged. 55 Therefore, in View A-A of FIG. 3, the region where the holes 110 can be provided is between two circumferentially adjacent ribs 161 and between the outer peripheral surface 47b of the combustor basket 47 and the inner peripheral surface 163a of the ring member 163. This partially annular region 60 is referred to as a hole arrangement area 105 (see FIG. 6).

In the hole arrangement area 105, the region close to the combustor basket 47 is also referred to as an inner region 108a, and the region close to the combustor casing 45 is also referred to as an outer region 108b.

65 For example, in FIG. 6, the region below the imaginary line Lv of the two-dotted dashed line extending in the right-left direction may be the inner region 108a, and the

region above the imaginary line L_v may be the outer region **108b**. The inner region **108a** and the outer region **108b** do not have to be in contact with each other across the imaginary line L_v , but the inner region **108a** and the outer region **108b** may be separated from each other in the radial direction. Further, in FIG. 6, the imaginary line L_v is illustrated as a straight line extending in the right-left direction, but the imaginary line L_v may be a curved line. For example, the imaginary line L_v may have an arc shape centered on the central axis AX of the combustor basket **47**.

The ligament ratio is a value (P_2/P_1) obtained by dividing the distance P_2 between the outer peripheral edges **10** of two adjacent holes **110** of the plurality of holes **110** by the distance P_1 between the centers of the two holes **110**. Therefore, the larger the ligament ratio, the larger the distance P_2 between the outer peripheral edges **109** of the two adjacent holes **110** relative to the distance P_1 between the centers of the two holes **110**, and thus the larger the proportion of the portion without the holes **110**, i.e., the portion corresponding to a frame in the perforated plate **100**. Accordingly, the larger the ligament ratio, the smaller the aperture ratio of the holes **110** but the larger the area of the region without the holes **110**, and the greater the strength of the perforated plate **100**.

Therefore, as described above, when the perforated plate **100** is configured such that the inner region **108a** has a larger average value of the ligament ratio (P_2/P_1) than the outer region **108b**, the proportion of the area of the region without the holes **110** per unit area in the perforated plate **100** is larger in the inner region **108a** than in the outer region **108b**, so that the strength of the perforated plate **100** is improved. As a result, the stress on the perforated plate **100**, which tends to increase from the radially outer side to the radially inner side as described above, can be effectively alleviated while suppressing the effect on the aperture ratio of the holes **110**.

In some embodiments, the perforated plate **100** may have a radial distribution in which the ligament ratio increases from the radially outer side to the radially inner side at least in a partial region of the hole arrangement area **105**.

With this configuration, at least in the partial region of the hole arrangement area **105**, the proportion of the area of the region without the holes **110** per unit area in the perforated plate **100** increases from the radially outer side to the radially inner side, so that the strength of the perforated plate **100** is improved. As a result, the stress on the perforated plate **100**, which tends to increase from the radially outer side to the radially inner side as described above, can be effectively alleviated while suppressing the effect on the aperture ratio of the holes **110**.

In some embodiments, the perforated plate **100** has a plurality of radially extending support members (ribs **161**) arranged in the circumferential direction. The hole arrangement area **105** is a partially annular region partitioned in the circumferential direction by adjacent support members (ribs **161**). The perforated plate **100** may have a radial distribution in which the ligament ratio increases from the radially outer side to the radially inner side in a circumferentially central portion of the partially annular region (hole arrangement area **105**) as the partial region of the hole arrangement area **105**.

With this configuration, at least in the circumferentially central portion of the hole arrangement area **105**, the proportion of the area of the region without the holes **110** per unit area in the perforated plate **100** increases from the radially outer side to the radially inner side, so that the strength of the perforated plate **100** is improved. As a result,

the stress on the perforated plate **100**, which tends to increase from the radially outer side to the radially inner side as described above, can be effectively alleviated while suppressing the effect on the aperture ratio of the holes **110**.

In some embodiments, the perforated plate **100** may be configured to have a radial distribution in which the ligament ratio (P_2/P_1) increases from the radially outer side to the radially inner side at least in a circumferentially central region **107** of the partially annular hole arrangement area **105** with the plurality of through holes (holes **110**).

With this configuration, at least in the circumferentially central region **107** of the hole arrangement area **105**, the proportion of the area of the region without the holes **110** per unit area in the perforated plate **100** increases from the radially outer side to the radially inner side, so that the strength of the perforated plate **100** is improved. As a result, the stress on the perforated plate **100**, which tends to increase from the radially outer side to the radially inner side as described above, can be effectively alleviated while suppressing the effect on the aperture ratio of the holes **110**.

In the embodiment shown in FIG. 6, in the hole arrangement area **105**, holes **110** are aligned in the right-left direction to form a row, and multiple rows of holes **110** are arranged in the upper-lower direction.

More specifically, in the embodiment shown in FIG. 6, the right-left direction coincides with the extension direction (tangential direction) of a tangent to an imaginary circle (not shown) centered on the central axis AX of the combustor basket **47** at the circumferentially central position of the hole arrangement area **105**. That is, in the embodiment shown in FIG. 6, the holes **110** are aligned in the tangential direction.

Further, in the embodiment shown in FIG. 6, the ligament ratio in the lower three rows of the multiple rows of holes **110** is larger than the ligament ratio in the upper four rows of the multiple rows of holes **110**.

For example, in the embodiment shown in FIG. 6, of the three holes **110** within the circle surrounded by the dashed line, the hole **110** on the left side of the two holes **110** arranged in the tangential direction is referred to as a left hole **110L**, and the hole **110** on the right side of the two holes **110** arranged in the tangential direction is referred to as a right hole **110R**. Further, of the three holes **110** within the circle surrounded by the dashed line, the hole **110** above the two holes **110** arranged in the tangential direction is referred to as an upper hole **110U**.

Regarding the three holes **110** within the dashed circle, the ligament ratio (P_{2a}/P_{1a}) for the left hole **110L** and the right hole **110R**, the ligament ratio (P_{2b}/P_{1b}) for the left hole **110L** and the upper hole **110U**, and the ligament ratio (P_{2c}/P_{1c}) for the right hole **110R** and the upper hole **110U** may be the same.

Alternatively, of the three ligament ratios, one ligament ratio may be different from the other two ligament ratios, or all three ligament ratios may be different.

In some embodiments, in the perforated plate **100**, a circumferential ligament ratio which is an average value of the ligament ratio in the circumferential direction may increase from the radially outer side to the radially inner side at least in a partial region of the hole arrangement area **105**.

With this configuration, the area of the region without the holes **110** increases from the radially outer side to the radially inner side in the partial region, so that the strength of the perforated plate **100** is improved.

In some embodiments, in the perforated plate **100**, a circumferential ligament ratio which is an average value of

the ligament ratio in the circumferential direction may increase from the radially outer side to the radially inner side.

With this configuration, even if the ligament ratio decreases from the radially outer side to the radially inner side in a part of the perforated plate 100 in the circumferential direction, the ligament ratio increases from the radially outer side to the radially inner side as a whole in the circumferential direction. Accordingly, the area of the region without the holes 110 increases from the radially outer side to the radially inner side over the entire circumference, so that the strength of the perforated plate 100 is improved.

FIG. 7A is an example of a graph showing a radial distribution of ligament ratio, for example, a radial direction of ligament ratio in the embodiment shown in FIG. 6. In the graph shown in FIG. 7A, the horizontal axis represents the radial position, and the vertical axis represents the ligament ratio.

FIG. 7B is an example of a graph showing a radial distribution of increase rate of ligament ratio in the graph shown in FIG. 7A, for example, a radial direction of increase rate of ligament ratio in the embodiment shown in FIG. 6. In the graph shown in FIG. 7B, the horizontal axis represents the radial position, and the vertical axis represents the increase rate of ligament ratio.

Here, the increase rate of ligament ratio is a ratio of change in ligament ratio to change in radial position. More specifically, the increase rate of ligament ratio is a ratio of increase in ligament ratio to change in radial position toward the radially inner side.

In the graphs shown in FIGS. 7A and 7B and later-described graphs, the radial position of a radially inner end portion 105a of the hole arrangement area 105 (see FIG. 6) is 0% and the radial position of a radially outer end portion 105b of the hole arrangement area 105 is 100%.

As shown in FIG. 7A, in the embodiment shown in FIG. 6, the ligament ratio is different between the radially inner side and the radially outer side of a radial boundary position, but the ligament ratio is constant within the region on the radially inner side of the boundary position regardless of the radial position. Similarly, the ligament ratio is constant within the region on the radially outer side of the boundary position regardless of the radial position.

As shown in FIG. 7B, for example in the embodiment shown in FIG. 6, the increase rate of ligament ratio is positive and relatively large at the boundary position, while it is zero at the other radial positions.

FIG. 8A is another example of a graph showing a radial distribution of ligament ratio. In the graph shown in FIG. 8A, the horizontal axis represents the radial position, and the vertical axis represents the ligament ratio.

FIG. 8B is an example of a graph showing a radial distribution of increase rate of ligament ratio in the graph shown in FIG. 8A. In the graph shown in FIG. 8B, the horizontal axis represents the radial position, and the vertical axis represents the increase rate of ligament ratio.

For example, in the graph shown in FIG. 8A, the ligament ratio increases linearly toward the radially inner side. That is, in the graph shown in FIG. 8A, the increase rate of ligament ratio is a constant positive value regardless of the radial position, as shown in FIG. 8B.

FIG. 9A is another example of a graph showing a radial distribution of ligament ratio. In the graph shown in FIG. 9A, the horizontal axis represents the radial position, and the vertical axis represents the ligament ratio.

FIG. 9B is an example of a graph showing a radial distribution of increase rate of ligament ratio in the graph

shown in FIG. 9A. In the graph shown in FIG. 9B, the horizontal axis represents the radial position, and the vertical axis represents the increase rate of ligament ratio.

For example, in the graph shown in FIG. 9A, in each of the thin and bold graph lines, the ligament ratio increases toward the radially inner side, while the rate of increase also increases toward the radially inner side.

In FIG. 9A, the thin graph line is a graph line when the increase rate of ligament ratio increases linearly toward the radially inner side, as indicated by the thin solid line in FIG. 9B, for example.

In FIG. 9A, the bold graph line is a graph line when the increase rate of ligament ratio increases toward the radially inner side while the rate of increase also increases toward the radially inner side, as indicated by the bold solid line in FIG. 9B, for example.

The increase rate of ligament ratio may not monotonically increase toward the radially inner side, but may be constant in a certain radial region regardless of the radial position, as indicated by the dashed line or the dotted and dashed line in FIG. 9B, for example.

FIG. 10A is another example of a graph showing a radial distribution of ligament ratio. In the graph shown in FIG. 10A, the horizontal axis represents the radial position, and the vertical axis represents the ligament ratio.

FIG. 10B is an example of a graph showing a radial distribution of increase rate of ligament ratio in the graph shown in FIG. 10A. In the graph shown in FIG. 10B, the horizontal axis represents the radial position, and the vertical axis represents the increase rate of ligament ratio.

For example, as shown in FIG. 10A, the ligament ratio may increase toward the radially inner side, while the rate of increase decreases toward the radially inner side.

For example, as shown in FIG. 10B, the increase rate of ligament ratio may be positive but decrease toward the radially inner side.

For example, as indicated by each graph line in FIG. 9B, a second ratio may be larger than a first ratio, where the first ratio is the increase rate of ligament ratio, i.e., the ratio (Δr/Δd) of change Δr in ligament ratio to change Δd in radial position in a first radial range R1, and the second ratio is the ratio (Δr/Δd) in a second radial range R2 that is radially inward of the first radial range R1.

With this configuration, the ratio (increase rate of ligament ratio) is larger in a relatively radially inner region (e.g., second range R2) than in a relatively radially outer region (e.g., first range R1). Thus, the strength of the perforated plate 100 can be improved in the relatively radially inner region while ensuring the aperture ratio and thus the flow rate of air passing through the plurality of holes 110 in the relatively radially outer region.

For example, as indicated by the solid graph line in FIG. 9B, the increase rate of ligament ratio, i.e., the ratio (Δr/Δd) of change Δr in ligament ratio to change Δd in radial position may gradually increase from the radially outer side to the radially inner side.

With this configuration, the above-described ratio increases toward the radially inner side. Thus, the strength of the perforated plate 100 can be improved in the relatively radially inner region while ensuring the aperture ratio and thus the flow rate of air passing through the plurality of holes 110 in the relatively radially outer region.

The increase rate of ligament ratio may gradually increase from the radially outer side to the radially inner side at least in the circumferentially central region 107.

When the radial position of the radially inner end portion 105a of the hole arrangement area 105 (see FIG. 6) is 0%

11

and the radial position of the radially outer end portion **105b** of the hole arrangement area **105** is 100%, the ligament ratio according to some embodiments may have the following value.

For example, the ligament ratio may be 0.10 or more within the range of 0% or more and 50% or less of radial position of the hole arrangement area **105**.

For example, the ligament ratio may be 0.11 or more within the range of 0% or more and 25% or less of radial position of the hole arrangement area **105**.

For example, the ligament ratio may be 0.15 or more within the range of 0% or more and 12.5% or less of radial position of the hole arrangement area **105**.

(Aperture Ratio)

In the following description, the aperture ratio of the holes **110** in the perforated plate **100**, more specifically, the aperture ratio of the holes **110** in the hole arrangement area **105** is a value expressed as a percentage of the total area of the holes **110** per unit area in the hole arrangement area **105**.

In some embodiments, the aperture ratio of the plurality of holes **110** in the hole arrangement area **105** may be 45% or more and 70% or less.

If the aperture ratio is less than 45%, it may be difficult to ensure the flow rate of air passing through the plurality of holes **110**, that is, the amount of air required in the combustor **4**. Further, if the aperture ratio is more than 70%, the strength of the perforated plate **100** may be impaired.

Therefore, by setting the aperture ratio to 45% or more and 70% or less, the strength of the perforated plate **100** can be ensured while ensuring the flow rate of air passing through the plurality of holes **110**.

(Arrangement of Holes **110**)

For example, as shown in FIG. 6, in some embodiments, instead of each two circumferentially adjacent holes **110** being at the same radial position, multiple rows of holes **110**, each aligned in the right-left direction, may be arranged in multiple stages in the upper-lower direction. In other words, for example, as shown in FIG. 6, in some embodiments, the plurality of holes **110** may have a pair of holes **110** that are arranged adjacent to each other in the circumferential direction at different radial positions.

With this configuration, the arrangement density of the holes **110** can be relatively increased, so that the flow rate of air passing through the plurality of holes **110** can be ensured.

(Shape of Holes **110**)

For example, as shown in FIG. 6, in some embodiments, at least in the circumferentially central region **107**, the plurality of holes **110** may be round holes.

The holes **110** of round is easier to machine than the holes **110** of rectangular or the like.

(Size of Holes **110**)

FIG. 11 is a diagram showing an example of another embodiment of the size of holes **110**.

In the perforated plate **100** according to some embodiments, for example, as shown in FIG. 11, the plurality of holes **110** may include a plurality of first holes **111**, and at least one second hole **112** having a larger opening area than that of each first hole **111**.

For example, in the embodiment shown in FIG. 11, in the hole arrangement area **105** (see FIG. 6), two rows of second holes **112**, each aligned in the right-left direction, are arranged in the upper-lower direction. The number of second holes **112** in the radially inner row may be, for example, two, and the number of second holes **112** in the radially outer row may be, for example, four.

Even if one of the two adjacent holes **110** is the first hole **111** and the other is the second hole **112**, there may be a

12

radial distribution in which the ligament ratio of these two holes **111** and **112** increases from the radially outer side to the radially inner side.

For example, as in the embodiment shown in FIG. 11, the centers **C1** of at least some of the plurality of first holes **111** may be located radially outward and radially inward of an opening edge (outer peripheral edge **109**) of the second hole **112** and within a circumferential range **141** of the outer peripheral edge **109** of the second hole **112**.

Generally, airflow having passed through a hole with a relatively small opening area is more likely to maintain velocity in a radially central region of the airflow than airflow having passed through a hole with a relatively large opening area. Therefore, for example, according to the embodiment shown in FIG. 11, since the first holes **111** having a smaller opening area than that of the second hole **112** are arranged radially outward and radially inward of the second hole **112**, the difference in velocity (difference in pressure) between the air having passed through the first holes **111** and the air having passed through the second hole **112** increases, and a secondary flow is generated. This promotes mixing of the air having passed through the first holes **111** and the air having passed through the second hole **112**, suppressing an unbalanced air flow in the combustor **4**.

For example, when the radial position of the radially inner end portion **105a** of the hole arrangement area **105** (see FIG. 6) is 0% and the radial position of the radially outer end portion **105b** of the hole arrangement area **105** is 100%, the radial position of the center **C2** of the at least one second hole **112** may be within the range of 25% or more and 75% or less.

If the radial position of the center **C2** of the at least one second hole **112** is out of this range, there is a risk of insufficient mixing between the air having passed through the first holes **111** and the air having passed through the second hole **112** as described above.

Therefore, with the configuration where the center **C2** of the at least one second hole **112** is within the above-described range, it is possible to promote mixing of the air having passed through the first holes **111** and the air having passed through the second hole **112** as described above, suppressing an unbalanced air flow in the combustor **4**.

For example, the hole diameter of the at least one second hole **112** may be 2.0 times or more and 3.0 times or less the hole diameter of the first hole **111**.

If the hole diameter of the second hole **112** is less than 2.0 times the hole diameter of the first hole **111**, the difference between the hole diameter of the second hole **112** and the hole diameter of the first hole **111** is small, and there is a risk of insufficient mixing between the air having passed through the first holes **111** and the air having passed through the second hole **112** as described above.

Further, if the hole diameter of the second hole **112** is more than 3.0 times the hole diameter of the first hole **111**, the difference in flow velocity (difference in pressure) between the air having passed through the first holes **111** and the air having passed through the second hole **112** further increases, and the pressure drop due to the generated secondary flow increases to such an extent that the effect of this pressure drop cannot be ignored.

Therefore, with the configuration where the hole diameter of the at least one second hole **112** is 2.0 times or more and 3.0 times or less the hole diameter of the first hole **111**, it is possible to promote mixing of the air having passed through the first holes **111** and the air having passed through the second hole **112** as described above, while suppressing the effect of pressure drop due to the secondary flow.

13

FIG. 12 is a diagram showing an example of another embodiment of the size of holes 110.

FIG. 13 is a diagram showing an example of another embodiment of the size of holes 110.

In the perforated plate 100 according to some embodiments, for example, as shown in FIG. 12, the plurality of holes 110 may include a plurality of first holes 111, at least one second hole 112 having a larger opening area than that of each first hole 111, and at least one third hole 113 having a smaller opening area than that of each first hole 111.

In the perforated plate 100 according to some embodiments, for example, as shown in FIG. 13, the plurality of holes 110 may include a plurality of first holes 111, and at least one third hole 113 having a smaller opening area than that of each first hole 111.

The hole diameter of the third hole may be, for example, 0.3 times or more and 0.8 times or less the hole diameter of the first hole.

For example, as shown in FIG. 12, the third hole 113 may be provided in a region of the perforated plate 100 shown in FIG. 11 where the first holes 111 and the second holes 112 do not exist. For example, as shown in FIG. 13, the third hole 113 may be provided in a region of the perforated plate 100 shown in FIG. 6 where the first holes 111 do not exist. With this configuration, the opening area in the perforated plate 100 can be increased, and the flow rate of the compressed air passing through the perforated plate 100 can be increased.

Even if one of the two adjacent holes 110 is the first hole 111 and the other is the third hole 113, there may be a radial distribution in which the ligament ratio of these two holes 111 and 113 increases from the radially outer side to the radially inner side.

Similarly, even if one of the two adjacent holes 110 is the second hole 112 and the other is the third hole 113, there may be a radial distribution in which the ligament ratio of these two holes 112 and 113 increases from the radially outer side to the radially inner side.

The combustor 4 according to some embodiments is provided with the perforated plate 100 according to any one of the above-described embodiments. Thereby, it is possible to achieve the combustor 4 with improved durability of the perforated plate 100 while ensuring the amount of air passing through the perforated plate 100.

The gas turbine 1 according to some embodiments is provided with the above-described combustor 4. Thereby, it is possible to improve the reliability of the gas turbine 1.

The present disclosure is not limited to the embodiments described above, but includes modifications to the embodiments described above, and embodiments composed of combinations of those embodiments.

For example, the holes 110 according to the above-described embodiments may be arranged in the circumferential direction with respect to the central axis AX of the combustor basket 47, or may be arranged at random.

The contents described in the above embodiments would be understood as follows, for instance.

(1) A perforated plate 100 for a gas turbine combustor 4 according to at least one embodiment of the present disclosure is a perforated plate 100 provided between a combustor basket 47 and a combustor casing 45 of the gas turbine combustor 4 and fixed to an outer peripheral portion of the combustor basket 47. In a hole arrangement area 105 with a plurality of through holes (holes 110) of the perforated plate 100, a region close to the combustor basket 47 (inner region 108a) has a larger average value of a ligament ratio than a region close to the combustor casing 45 (outer region 108b), where the

14

ligament ratio is obtained by dividing a distance P2 between outer peripheral edges 109 of two adjacent holes 110 of the plurality of through holes (holes 110) by a distance P1 between the centers of the two holes 110.

With the above configuration (1), in the hole arrangement area 105, the proportion of the area of the region without the holes 110 per unit area in the perforated plate 100 is larger in the region close to the combustor basket 47 (inner region 108a) than in the region close to the combustor casing 45 (outer region 108b), so that the strength of the perforated plate 100 is improved. As a result, the stress on the perforated plate 100, which tends to increase from the radially outer side to the radially inner side as described above, can be effectively alleviated while suppressing the effect on the aperture ratio of the holes 110.

(2) In some embodiments, in the above configuration (1), the perforated plate 100 may have a radial distribution in which the ligament ratio increases from the radially outer side to the radially inner side at least in a partial region of the hole arrangement area 105.

With the above configuration (2), at least in the partial region of the hole arrangement area 105, the proportion of the area of the region without the holes 110 per unit area in the perforated plate 100 increases from the radially outer side to the radially inner side, so that the strength of the perforated plate 100 is improved. As a result, the stress on the perforated plate 100, which tends to increase from the radially outer side to the radially inner side as described above, can be effectively alleviated while suppressing the effect on the aperture ratio of the holes 110.

(3) In some embodiments, in the above configuration (2), the perforated plate 100 has a plurality of radially extending support members (ribs 161) arranged in the circumferential direction. The hole arrangement area 105 is a partially annular region partitioned in the circumferential direction by adjacent support members (ribs 161). The perforated plate 100 may have the above-described radial distribution in a circumferentially central portion of the partially annular region as the partial region.

With the above configuration (3), at least in the circumferentially central portion of the hole arrangement area 105, the proportion of the area of the region without the holes 110 per unit area in the perforated plate 100 increases from the radially outer side to the radially inner side, so that the strength of the perforated plate 100 is improved. As a result, the stress on the perforated plate 100, which tends to increase from the radially outer side to the radially inner side as described above, can be effectively alleviated while suppressing the effect on the aperture ratio of the holes 110.

(4) In some embodiments, in the above configuration (2) or (3), in the perforated plate 100, a circumferential ligament ratio which is an average value of the ligament ratio in the circumferential direction may increase from the radially outer side to the radially inner side at least in a partial region of the hole arrangement area 105.

With the above configuration (4), the area of the region without the holes 110 increases from the radially outer side to the radially inner side in the partial region, so that the strength of the perforated plate 100 is improved.

(5) In some embodiments, in any one of the above configurations (2) to (4), in the above-described radial distribution, a second ratio may be larger than a first ratio, where the first ratio is a ratio $(\Delta r / \Delta d)$ of change Δr in ligament ratio to change Δd in radial position in

15

a first radial range **R1**, and the second ratio is a ratio ($\Delta r/\Delta d$) of change Δr in ligament ratio to change Δd in radial position in a second radial range **R2** that is radially inward of the first radial range **R1**.

With the above configuration (5), the ratio ($\Delta r/\Delta d$) is larger in a relatively radially inner region than in a relatively radially outer region. Thus, the strength of the perforated plate **100** can be improved in the relatively radially inner region while ensuring the aperture ratio and thus the flow rate of air passing through the plurality of holes **110** in the relatively radially outer region.

(6) In some embodiments, in the above configuration (5), in the above-described radial distribution, the ratio ($\Delta r/\Delta d$) may gradually increase from the radially outer side to the radially inner side.

With the above configuration (6), the ratio ($\Delta r/\Delta d$) increases toward the radially inner side. Thus, the strength of the perforated plate **100** can be improved in the relatively radially inner region while ensuring the aperture ratio and thus the flow rate of air passing through the plurality of holes **110** in the relatively radially outer region.

(7) In some embodiments, in any one of the above configurations (1) to (6), the aperture ratio of the plurality of through holes (holes **110**) in the hole arrangement area **105** may be 45% or more and 70% or less.

If the aperture ratio is less than 45%, it may be difficult to ensure the flow rate of air passing through the plurality of holes **110**, that is, the amount of air required in the combustor **4**. Further, if the aperture ratio is more than 70%, the strength of the perforated plate **100** may be impaired.

With the above configuration (7), the strength of the perforated plate **100** can be ensured while ensuring the flow rate of air passing through the plurality of holes **110**.

(8) In some embodiments, in any one of the above configurations (1) to (7), the plurality of through holes (holes **110**) may have a pair of holes **110** that are arranged adjacent to each other in the circumferential direction at different radial positions.

With the above configuration (8), the arrangement density of the holes **110** can be relatively increased, so that the flow rate of air passing through the plurality of holes **110** can be ensured.

(9) In some embodiments, in any one of the above configurations (1) to (8), the plurality of through holes (holes **110**) may include a plurality of first holes **111**, and at least one second hole **112** having a larger opening area than that of each first hole **111**. The centers **C1** of at least some of the plurality of first holes **111** may be located radially outward and radially inward of an opening edge (outer peripheral edge **109**) of the second hole **112** and within a circumferential range **141** of the outer peripheral edge (outer peripheral edge **109**) of the second hole **112**.

Generally, airflow having passed through a hole with a relatively small opening area is more likely to maintain velocity in a radially central region of the airflow than airflow having passed through a hole with a relatively large opening area. With the above configuration (9), since the first holes **111** having a smaller opening area than that of the second hole **112** are arranged radially outward and radially inward of the second hole **112**, the difference in velocity (difference in pressure) between the air having passed through the first holes **111** and the air having passed through the second hole **112** increases, and a secondary flow is generated. This promotes mixing of the air having passed

16

through the first holes **111** and the air having passed through the second hole **112**, suppressing an unbalanced air flow in the combustor **4**.

(10) In some embodiments, in the above configuration (9), when the radial position of the radially inner end portion **105a** of the hole arrangement area **105** is 0% and the radial position of the radially outer end portion **105b** of the hole arrangement area **105** is 100%, the radial position of the center **C2** of the at least one second hole **112** may be within the range of 25% or more and 75% or less.

If the radial position of the center **C2** of the at least one second hole **112** is out of this range, there is a risk of insufficient mixing between the air having passed through the first holes **111** and the air having passed through the second hole **112** as described above.

With the above configuration (10), it is possible to promote mixing of the air having passed through the first holes **111** and the air having passed through the second hole **112** as described above, suppressing an unbalanced air flow in the combustor **4**.

(11) In some embodiments, in the above configuration (9) or (10), the hole diameter of the at least one second hole **112** may be 2.0 times or more and 3.0 times or less the hole diameter of the first hole **111**.

If the hole diameter of the second hole **112** is less than 2.0 times the hole diameter of the first hole **111**, the difference between the hole diameter of the second hole **112** and the hole diameter of the first hole **111** is small, and there is a risk of insufficient mixing between the air having passed through the first holes **111** and the air having passed through the second hole **112** as described above.

Further, if the hole diameter of the second hole **112** is more than 3.0 times the hole diameter of the first hole **111**, the difference in flow velocity (difference in pressure) between the air having passed through the first holes **111** and the air having passed through the second hole **112** further increases, and the pressure drop due to the generated secondary flow increases to such an extent that the effect of this pressure drop cannot be ignored.

With the above configuration (11), it is possible to promote mixing of the air having passed through the first holes **111** and the air having passed through the second hole **112** as described above, while suppressing the effect of pressure drop due to the secondary flow.

(12) A gas turbine combustor **4** according to at least one embodiment of the present disclosure is provided with the perforated plate **100** having any one of the above configurations (1) to (11).

With the above configuration (12), it is possible to achieve the gas turbine combustor **4** with improved durability of the perforated plate **100** while ensuring the amount of air passing through the perforated plate **100**.

(13) A gas turbine **1** according to at least one embodiment of the present disclosure is provided with the gas turbine combustor **4** having the above configuration (12).

With the above configuration (13), it is possible to improve the reliability of the gas turbine **1**.

113 Third hole

The invention claimed is:

1. A perforated plate for a gas turbine combustor, provided between a combustor basket and a combustor casing of the gas turbine combustor and fixed to an outer peripheral portion of the combustor basket,

wherein, in a hole arrangement area with a plurality of through holes of the perforated plate, a region close to the combustor basket has a larger average value of a ligament ratio than a region close to the combustor casing, where the ligament ratio is obtained by dividing a distance between outer peripheral edges of two adjacent holes of the plurality of through holes by a distance between centers of the two holes,

wherein the perforated plate has a radial distribution in which the ligament ratio increases from a radially outer side to a radially inner side at least in a partial region of the hole arrangement area, and

wherein, in the radial distribution, a second ratio is larger than a first ratio, where the first ratio is a ratio of change in the ligament ratio to change in radial position in a first radial range, and the second ratio is a ratio of change in the ligament ratio to change in radial position in a second radial range that is radially inward of the first radial range.

2. The perforated plate for a gas turbine combustor according to claim 1,

wherein the perforated plate has a plurality of radially extending support members arranged in a circumferential direction,

wherein the hole arrangement area is a partially annular region partitioned in the circumferential direction by adjacent support members of the plurality of support members, and

wherein the perforated plate has the radial distribution in a circumferentially central portion of the partially annular region as the partial region.

3. The perforated plate for a gas turbine combustor according to claim 1,

wherein, in the perforated plate, a circumferential ligament ratio which is an average value of the ligament ratio in the circumferential direction increases from the radially outer side to the radially inner side at least in the partial region.

4. The perforated plate for a gas turbine combustor according to claim 1,

wherein, in the radial distribution, the ratio gradually increases from the radially outer side to the radially inner side.

5. The perforated plate for a gas turbine combustor according to claim 1,

wherein the plurality of through holes has a pair of holes that are arranged adjacent to each other in a circumferential direction at different radial positions.

6. A gas turbine combustor, comprising the perforated plate according to claim 1.

7. A gas turbine, comprising the gas turbine combustor according to claim 6.

8. A perforated plate for a gas turbine combustor, provided between a combustor basket and a combustor casing of the gas turbine combustor and fixed to an outer peripheral portion of the combustor basket,

wherein, in a hole arrangement area with a plurality of through holes of the perforated plate, a region close to the combustor basket has a larger average value of a ligament ratio than a region close to the combustor casing, where the ligament ratio is obtained by dividing a distance between outer peripheral edges of two adjacent holes of the plurality of through holes by a distance between centers of the two holes, and

wherein an aperture ratio of the plurality of through holes in the hole arrangement area is 45% or more and 70% or less.

9. A perforated plate for a gas turbine combustor, provided between a combustor basket and a combustor casing of the gas turbine combustor and fixed to an outer peripheral portion of the combustor basket,

wherein, in a hole arrangement area with a plurality of through holes of the perforated plate, a region close to the combustor basket has a larger average value of a ligament ratio than a region close to the combustor casing, where the ligament ratio is obtained by dividing a distance between outer peripheral edges of two adjacent holes of the plurality of through holes by a distance between centers of the two holes,

wherein the plurality of through holes includes a plurality of first holes and at least one second hole having a larger opening area than that of each first hole, and wherein the centers of at least some of the plurality of first holes are located radially outward and radially inward of an opening edge of the second hole and within a circumferential range of the opening edge of the second hole.

10. The perforated plate for a gas turbine combustor according to claim 9,

wherein a radial position of the center of the least one second hole is within a range of 25% or more and 75% or less when the radial position of a radially inner end portion of the hole arrangement area is 0% and the radial position of a radially outer end portion of the hole arrangement area is 100%.

11. The perforated plate for a gas turbine combustor according to claim 9,

wherein a hole diameter of the at least one second hole is 2.0 times or more and 3.0 times or less a hole diameter of each first hole.
